UNITED STATES PATENT OFFICE.

REINHOLD H. WAPPLER, OF YONKERS, NEW YORK, ASSIGNOR TO WAPPLER ELECTRIC CO., INC., A CORPORATION OF NEW YORK.

ELECTRODE.

Application filed January 19, 1921. Serial No. 438,298.

To all whom it may concern:

Be it known that I, REINHOLD H. WAPPLER, a citizen of the United States, residing in Yonkers, county of Westchester, and State of New York, have invented certain new and useful Improvements in Electrodes, of which the following is a full, clear, and concise description.

My invention relates to electrodes, and 10 particularly to electrodes suitable for medical and therapeutical use.

More particularly stated, I seek to produce an electrode especially adapted for applying high frequency currents directly to 15 the human skin, without danger of producing burns or blisters, and without producing disagreeable prickling sensations.

Heretofore it has been common practice to use a pair of electrodes for the purpose 20 of applying to the surface of the skin direct and interrupted galvanic currents, and also faradic currents. Some effort has been made to apply high frequency current to the skin, but difficulty has been experienced 25 in providing electrodes entirely suitable for the purpose. When such currents are used with dry electrodes of metal or other material of low ohmic resistance applied directly to the skin, the currents have not 30 been properly distributed; the result being that the application has been painful to the patient and slightly injurious to the skin. Moreover the skin is not always in the 35 same condition, being sometimes moist and sometimes dry. Hence the electrodes of the kind just mentioned are not uniform in their action upon the skin. If the skin happens to be excessively dry and high frequency currents are applied to it in such 40 manner as to be effective, the skin is likely to be injured and the nerves of the patient unduly irritated.

Sometimes high frequency currents have 45 been applied to the body by means of pads of absorbent material moistened with water. In such instances it has been found quite difficult to get the amount of moisture just right, the result being that frequently the water held in the pad became overheated 50 and scalded the skin. Thus while the application of moisture to the skin has tended to diminish the ohmic resistance of the skin and of parts of the electrode in immediate

contact with the skin, the danger of scalding or burning, or of diffusing the current 55 unequally through the skin has detracted from the beneficial effects of the moisture carried by the electrode.

What I seek to do my present invention is to produce an electrode suitable for use 60 with high frequency currents as well as with currents of other kinds, and in which I make provision for the retention of moisture, but in which I enable the high frequency current to reach the skin independently to a great extent of the resistance of 65 the moisture and of any absorbent medium used for retaining the moisture. In doing this, I also preserve the softness and smoothness well known in the pad electrode, so that 70 my improved electrode, when pressed against or fitted upon an uneven or irregular surface of the body, or upon a part in which there is pain or soreness, fits accurately and neatly against the same, its pressure at all 75 points being substantially uniform.

Reference is made to the accompanying drawing forming a part of this specification, in which like reference characters indicate like parts throughout the several figures. 80

Figure 1 is a substantially central section through my improved electrode.

Figure 2 is an end elevation of the device. Figure 3 is a view partly in elevation and 85 partly diagrammatic, of a pair of my improved electrodes as applied to an anatomical member, such as an arm or a leg.

A handle 4 carries a metallic holder 5. For this purpose the handle is provided with a hole 6, and the holder 5 is provided with 90 a pin 7 which fits tightly into this hole. The holder 5 is further provided with a pin 9. The pins 7 and 9 are integral with the holder 5. A binding post 8 is mounted upon the holder 5.

Fitted neatly upon the pin 9 is a shank 10 made of metal and carrying a metallic disk 11 integral with it.

Engaging the face of the disk 11 is a pad member 12, which may consist of a knob-like ball of cotton or wool, a flattened ball of thread, a handkerchief or a towel, or a mat of textile material. This pad member is held in position by netting 13, of which any number of layers suitable for the purpose may be employed. In this particular

instance two layers are shown. The netting is made of metal, preferably in the form of wire or tinsel strips knitted or woven, very fine, soft and pliable. The netting is 5 provided with reverting portions 14, brought into engagement with the adjacent outer surface of the metallic disk 11. Folds 15 are made in the netting as it is bent back upon the disk 11.

10 Mounted upon the disk 11, and secured thereto by screws 17, is a clamping ring 16, loosely encircling the shank 10 and made of metal. The purpose of the clamping ring is to press the adjacent portions of the netting directly and tightly against the disk 11, as may be understood from Figure 1. Thus the ohmic resistance from the binding post 8 to any chosen point upon the outer face of the netting is very low, and to any considerable 15 surface of the netting is practically negligible. While the pad member 12 is usually moistened when ready for use, and while the moisture it thus acquires has of course a tendency to lower its ohmic resistance, the 20 ohmic resistance of the electrode as a whole is too low for the current to burn or otherwise injure the skin or cause any disagreeable sensation, even when high frequency currents are used and the amount of moisture in the pad member is reduced to a minimum.

In Figure 3, I show a pair of my improved electrodes as connected with conductors 18, 19, and as pressed against an anatomical 35 member 20, such as an arm or a leg. The conductors 18, 19 are either wires or cords, and are preferably connected with a source of high frequency current. If desired, however, they may be connected with a galvanic 40 battery or with a faradic apparatus.

I do not limit myself to the particular construction shown, nor to any particular kind of current or currents to be employed, nor to any special medical or therapeutical 45 use for my device, the scope of my invention being co-extensive with my claims.

Having thus described my invention, what I claim as new and desire to secure by Letters Patent is as follows:

50 1. An electrode of the character described, comprising a holder, a pad member engaging said holder and made of such material as to become conducting when moistened, and a container enveloping said pad and made of conducting material, said container being in the form of a netting.

60 2. An electrode of the character described, comprising a metallic member, a pad member engaging said metallic member and made of such material as to become conducting when moist, a netting made of metal and engaging said pad member, said netting being connected with said metallic member, and an electrical connection for said metallic member.

65 3. An electrode of the character described, comprising a metallic shank and a metallic disk carried by said shank, a pad member engaging said disk and made of porous material in order to retain moisture and 70 while moist to serve as a conductor, and a metallic netting secured to said metallic disk and engaging said pad member so as to press the same against said disk.

75 4. An electrode of the character described, comprising a shank of conducting material, means for supplying an electric current to said shank, a pad member supported by said shank and while in action serving as a conductor, and a flexible metallic member 80 engaging said pad member and together therewith constituting a conducting electrode pad, said flexible member being of low ohmic resistance as compared with said pad member.

85 5. An electrode comprising a shank of conducting material, an electric connection for supplying currents to said shank, a pad member carried by said shank and having 90 while in action a low ohmic resistance in order to serve as a conductor, and a metallic netting enclosing said pad member and together therewith being in conductive communication with said shank, for the purpose 95 of distributing electric currents from said shank.

100 6. An electrode of the character described, comprising a shank made of electrically conducting material, a metallic disk carried by said shank, an electrically conducting pad member engaging said metallic disk, a metallic netting enclosing said pad member and connected with said metallic disk, so that said metallic netting and said pad member coact with each other in distributing 105 electric currents from said disk, and an electrical connection for said disk.

110 7. An electrode comprising a metallic shank, means for supplying an electric current thereto, and an absorbent member disposed adjacent said metallic shank and adapted to retain moisture so as to serve as a conductor, and a netting of conducting material engaging said absorbent member and in conductive relation thereto, said netting 115 being also in direct electrical communication with said shank.

120 8. An electrode, comprising a shank of conducting material provided with an enlarged portion, a pad member of absorbent material disposed adjacent said enlarged portion and when moistened serving as a conductor, a metallic netting engaging said pad member for the purpose of holding the same in position, and means for holding 125 said metallic netting in engagement with said enlarged portion.

130 9. An electrode comprising a disk, means for supplying electric current to said disk, a pad of absorbent material engaging said

disk and when moistened serving as a conductor, a soft and flexible metallic netting engaging said pad and provided with portions engaging said disk, a clamping ring 5 engaging said portions of said metallic netting, and means for forcing said clamping ring toward said disk.

10. An electrode comprising a pad made of absorbent material and adapted when moistened to conduct electric currents, a netting of conducting material enclosing said pad, and means for supplying electric current to said pad and to said netting.

REINHOLD H. WAPPLER.
